REFRIGERATING APPARATUS

Robert H. Geiger, Dayton, Ohio

Application July 16, 1940, Serial No. 345,786

8 Claims. (Cl. 62—108.5)

My invention relates to refrigeration and particularly to individual freezing trays and a common support therefor, whereby a single tray may be removed from the support without disturbing any of the remaining trays on the support, to remove an ice cube or any other frozen matter in the tray, after said matter has been frozen into a solid mass.

My invention is well adapted to be used in the freezing compartments of any type of refrigerator whether it be electric, gas or any other kind of chemically operated refrigerator.

In many such refrigerators now on the market the ice trays are arranged to hold a plurality of ice cubes and it is inconvenient and sometimes very difficult to get a single cube only, from the tray of multiple cubes.

Very often a person wishes only a single cube and where a plurality of cubes are made in a single tray it may be necessary to remove all cubes therefrom in order to get a single one of the cubes for use.

Therefore it is one of the objects of my invention to provide a novel ice, or other matter, mold for making only a single cube of ice, or single cube of other frozen matter, which can be readily and very easily taken from the refrigerator without disturbing the remaining cubes in the freezing compartment.

Another object of my invention is the provision of a novel supporting means for a plurality of individual freezing trays.

A further object is to provide the individual molds or trays with a novel expansion section whereby an ice cube or any other frozen matter can be very quickly and easily removed.

Another object of my invention is to provide such novel molds with a convenient handle and also with a novel support whereby the mold may be inverted over a cup or water glass and rested on the edge thereof while the frozen material is removed from the mold or tray into the cup or glass.

Another object of my invention is the provision of lugs or projections on the mold for cooperating with the support whereby only a very small surface of the mold rests on the common support thus eliminating, or at least reducing to a minimum, the freezing of the mold to the common support.

A still further object of my invention is to produce a novel common support for a plurality of individual molds or trays, constructed so that the molds can be placed on said support in one position only.

With these and other incidental objects in view my invention includes certain novel features of construction and combinations of parts, the essential elements of which are set forth in appended claims, and a preferred form or embodiment of which is hereinafter described with reference to the drawing which accompanies and forms part of this specification.

Of said drawing:

Fig. 1 is a view, partly in section, and partly broken away, showing my improved common support with two of the molds or trays thereon, one being sectioned.

Fig. 2 is a fragmentary plan view of the same, except the two trays are shown close together, and one of them is broken away.

Fig. 3 is an end view of the common support showing one of the molds or trays in position thereon.

Fig. 4 is a fragmentary enlarged plan view of the individual mold showing particularly the expansion section thereof.

Fig. 5 is a section on line 5—5 of Fig. 4 looking in the direction of the arrows.

Fig. 6 shows how the individual mold can be inverted and rested on the edge of a drinking glass to release the ice cube or other frozen matter, into the glass.

Detailed description

My novel common support for the individual molds comprises side rails 20 and 21 formed as loops which may be made of a solid material or a tubing, either of which is to be light in weight. These rails 20 and 21 are connected at their ends by rods 22. The rail 20 is lower than the rail 21 for a purpose to be hereinafter described.

My novel individual molds 25 are arranged side by side on the rails as shown in Figs. 1 and 2, and can be separately removed to obtain a single ice cube when desired without disturbing any of the remaining molds.

Each mold 25 is preferably made of a single piece and it may be manufactured of a spring non-rust metal. However I do not wish to limit my invention to any particular kind of metal or other material as many different kinds are available for such purposes.

The sides 26 and 27 (Figs. 2 and 3) and 28 and 29 (Figs. 1, 2, 4 and 5) are formed up from a base or bottom 30, and at an angle off the vertical.

The side 26 and a portion of the sides 28 and 29 have formed at the top thereof a single continuous flange 31, and the side 27 and another

portion of the sides 28 and 29 have formed at the top thereof a single continuous flange 32. All four sides 26, 27, 28 and 29 are tapered as shown and as above stated. These flanges 31 and 32 are arranged to leave openings 33 and 34 just above the expansion sections of the sides 28 and 29.

The sides 28 and 29 have semi-circular and V-shaped expansion sections 35 and 36 respectively which function by expanding when a person removes an ice cube or other frozen matter from the mold or tray 25. These expansion sections 35 and 36 run from a point near the center of the sides 28 and 29 at the bottom 30 and extend upwardly to positions slightly below the flanges 31 and 32.

Secured to the top of the left portion of the flange 31 by bolts or rivets 40 is a plate 41 having a boss 42 the top of which is curved as at 43 to form a rest for the mold or tray 25 when the latter is inverted over the top of a drinking glass 45 as shown in Fig. 6, or over any other receptacle into which it is desired to release an ice cube. The bolts or rivets 40 have heads 46 (Figs. 1 and 3) forming lugs which rest on the upper side of the rail 21 to support the mold 25, to aid in maintaining the mold 25 level.

The right portion of the flange 32 (Figs. 1, 2, 3 and 6) has secured thereto by bolts or rivets 50 a plate forming a handle 51. The handle is slotted to receive the flange 32 and to so locate said handle as to make it lower than the bottom of the heads of the bolts heads 46 for the plate 41. The bolts 50 have heads 53 resting on the top of the rail 20 to aid in maintaining the mold 25 level. The heads 46 and 53 are flat and therefore reduce to a minimum any freezing of the mold 25 to the rails 20 and 21, due to the fact that the tops of the rails are round.

These rails may be of any desired length depending upon the size of the freezing compartment in the refrigerator with which they are to be used. The length of the rails therefore will determine the number of molds or trays 25 which can be used in connection therewith.

From the above description it can be readily seen that it is very easy to remove only a single mold from the rails to obtain a single ice cube for use when desired, without having to remove more than one cube, and without disturbing any of the remaining cubes. As stated above this cannot be accomplished with many of the freezing trays now on the market.

Moreover as the rails are of different heights, the molds cannot be placed on the rails in any but the proper positions in which they are level whereby the water or other matter therein to be frozen cannot spill. The entire group of molds can be withdrawn from the freezing compartment by grasping the rod 22.

Due to my novel construction of the mold or tray 25, ice cubes can be very easily released from said tray by holding the handle and inverting the mold over a glass or other receptacle as shown in Fig. 6 and holding the bottom rigid and putting a slight pressure upwardly (as viewed in Fig. 6) with the thumb on the handle whereupon due to the expansion sections, the tray will flex sufficiently to release the ice cube or any other frozen matter that may be in the tray 25. The tray may be inverted on a kitchen work table or any other convenient place to release the cube.

The cube may also be released from the tray by using both hands and grasping the handle 51 and the plate 41-42 exerting a slight pull, away

from each other, on the handle and on the plate 41-42, whereupon the cube is immediately released from the tray due to the expansion sections 35 and 36. The above may be accomplished by holding the tray, or the tray may be set on a table on its bottom 30 and the cube can be freed from the tray in the same manner as just described, that is by pulling slightly, in opposite directions on the handle and on the plate 41-42.

10 While the form of mechanism herein shown and described is admirably adapted to fulfill the objects primarily stated, it is to be understood that my invention is not limited to the one form or embodiment shown, as it is susceptible of other embodiments, all coming within the scope of the claims which follow.

What I claim is:

1. In an apparatus of the class described, the combination of a plurality of members of varying sizes connected together near their ends, the bottoms of said members being in a horizontal plane, to form a common support for a plurality of individual freezing molds; and a plurality of individual freezing molds having means of 25 various heights projecting from opposite ends thereof to cooperate with the varying sized members whereby said molds are maintained in level positions relative to the bottoms of said members.

2. In an apparatus of the class described, the combination of two members of varying heights connected together near their ends to form a common support for a plurality of individual freezing molds; a plurality of individual freezing molds, each mold having a plurality of flanges 35 of equal height relative to its bottom; means secured to one flange of each mold for cooperating with one of said members; and means secured to another flange of each mold for cooperating with the lower one of said members for maintaining the molds level.

3. In an apparatus of the class described, the combination of a plurality of individual freezing molds each having lateral extensions of equal height relative to its bottom; a common support 45 for said molds comprising side members of varying heights and end members; means secured to one of said extensions of each mold to cooperate with the higher one of said side members; and means secured to another of said extensions of each mold to cooperate with another of said side members, both of said means functioning to maintain their associated molds level.

4. A freezing tray comprising a bottom, ends and sides; a plurality of extensions formed on said ends and sides and constructed to leave openings at the center of the top of the sides; and a plurality of expansion sections formed in the sides, said sections beginning at the junction of the bottom and the sides and extending upwardly to positions near the top of said sides and below said openings and increasing in size from the bottom to the top.

5. A freezing compartment comprising a bottom; ends and sides; a plurality of extensions formed on said ends and sides and providing openings midway of said ends; and a plurality of semi-circular-tapered sections formed in said sides intermediate said ends and adjacent said openings, said sections extending from the bottom to positions near the top and increasing in diameter from the bottom to the top.

6. A freezing tray having lateral extensions integral with the sides and ends of the tray, said extensions being constructed to form openings midway of the ends of the tray; expansion sec-

tions formed in the sides of the tray adjacent said openings to render the latter manually distortable to release any frozen matter in the tray; and means secured to one of said extensions to form a rest for said tray upon inverting the same to release said frozen matter.

7. A distortable freezing container to receive matter to be frozen; extensions on said container, one of said extensions being integral with one end and a portion of each side of the container, another of said extensions being integral with the other end and a portion of each side of the container, said extensions being constructed to provide openings substantially midway between the ends of the container; and oppositely disposed expansion sections in said sides of the

5 container; whereby a slight pressure exerted on said extensions causes the bond between the container and any frozen matter therein to be broken whereupon said frozen matter is immediately released from said container.

8. A freezing tray for an individual cube of frozen matter and having an expansion section in each of its sides; an extension on each of the ends of the tray; and extensions on each of 10 said sides and arranged to leave an opening above each of said expansion sections, each expansion section extending from the junction of its respective side and the bottom to a position near the top of said side and increasing in size as it nears 15 said position.
